DESIGN FOR A CLOCK CASING

Max Schlenker, La Salle, Ill.

Application October 15, 1936, Serial No. 65,317

Term of patent 7 years

To all whom it may concern:

Be it known that I, Max Schlenker, a citizen of the United States, residing in the city of La Salle, in the county of La Salle and State of Illinois, have invented a new, original, and ornamental Design for a Clock Casing, of which the following is a specification, reference being had to the accompanying drawing, forming a part thereof.

Fig. 1 is a front perspective view of a clock casing showing my new design, and

Fig. 2 is a diagrammatic plan view of same.

I claim:

The ornamental design for a clock casing, as shown.

MAX SCHLENKER.
